SPLITTING MACHINE

Thomas Baggott Clarke and Hubert Boothroyd, Leicester, England, assignors to United Shoe Machinery Corporation, Borough of Flemington, N. J., a corporation of New Jersey

Application October 31, 1938, Serial No. 237,964
In Great Britain November 24, 1937

8 Claims. (Cl. 69—13)

This invention relates to splitting machines for use in the manufacture of shoes and is herein illustrated as embodied in an improved machine of the general type disclosed in United States Letters Patent No. 2,100,431, granted November 30, 1937 on an application filed in our names.

The various features of the invention will be understood and appreciated from the following detailed description read in connection with the accompanying drawing, in which—

Fig. 1 is a front view, partly in section and partly broken away, of the illustrated splitting machine;

Figs. 2 and 3 are sectional views on lines II—II and III—III of Fig. 1; and

Fig. 4 is a detail view showing a pair of rolls which are used in the machine equipped to split heel-breast covering flaps from soles of shoes.

The illustrated machine is described with reference to splitting a layer of material of uniform thickness such, for example, as a heel-breast covering flap, from a leather sole which is of substantially uniform thickness but of varying density. The work piece supported by a table 20 (Figs. 1 and 2) is fed by upper and lower rolls 22, 24, respectively, against a splitting knife 26 secured to the main frame 28 by a screw 30 (Fig. 2) which passes through an elongated slot 32 in the knife and is threaded into the main frame. The layer of material split from the work piece passes through a gap 34 (Fig. 2) formed between a straight elongated cutting edge 36 of the knife and the upper feed roll 22 which is initially adjustable toward and away from the cutting edge of the knife but is not yieldable under pressure of the work. The thickness of the layer of material split from the work piece varies in accordance with the position of the upper roll 22 which may be referred to as a gage roll. The remaining portion of the split work piece passes between the cutting edge 36 of the knife 26 and the lower roll 24 which is yieldable away from the knife in accordance with the thickness of the work piece and the density 45 of the material of the work piece.

In order that the width of the gap 34 may be varied in accordance with the movement of the lower roll 24 toward and away from the knife 26 the upper roll 22 is operatively connected to the lower roll 24, the arrangement being such that vertical movement of the lower roll 24 in one direction will cause a proportionate but less vertical movement of the upper roll 22 in an opposite direction. The upper and lower rolls 55 22, 24 are of the same diameter and rotate at the

same speed, power being supplied to the rolls by gears 38 and 40, respectively, which are keyed to extensions of the rolls and are operated by suitable mechanism.

The lower roll 24 is rotatably mounted in 5 globular bearings 42 (Fig. 1) which seat in correspondingly shaped recesses formed in the forward ends of supporting arms 44 (Figs. 1 and 2), respectively, loosely mounted upon a horizontal shaft 46 (Fig. 2), the arrangement being such 10 that the lower roll may tip freely laterally should a work piece be tapered laterally or be more compressible along one side margin than the other. As the lower roll 24 moves downward about the shaft 46 it also moves forward thereby insuring 15 that adequate clearance for the lower portion of the work piece is provided at all times between the roll and the lower surface of the knife 26.

The lower roll 24 is normally held in a raised position by a pair of springs 48 the upper ends 20 of which are forced against the forward portions of the respective supporting arms 44 and the lower arms of which fit in bores (not shown) of the machine frame.

A bracket 50 (Figs. 1 and 2) is secured to the 25 main frame of the machine and has its ends closed by cover plates 52 (Fig. 1) and its under side partially closed by a cover plate 54 (Figs. 1 and 2). Slidably mounted in the bracket 50 above a horizontal upper roll adjusting slide 56 30 is a wedge bar 58 (Figs. 1, 2 and 3) which is movable widthwise of the machine in a direction parallel to and lengthwise of the feed rolls 22, 24. The wedge bar 58 is provided with flat upper and lower faces 60, 62 (Figs. 1 and 3) respectively, 35 inclined to each other, the distance between the upper and lower faces increasing toward the right as viewed in Fig. 1. Located between the lower inclined faces 62 of the wedge bar 58 and the upper horizontal face of the adjusting slide 40 56 are two movable blocks 64 (Figs. 1 and 3) which are prevented from being moved forward or rearward of the machine by the bracket 50 and laterally of the machine by the cover plates 52 and 54. The blocks 64 have horizontal lower 45 faces resting upon the flat upper face of the adjusting slide 56. The upper faces of the blocks 64 are arranged in parallel relation to the lower inclined faces 62 of the wedge bar 58 and between said faces are arranged friction rollers 66 50 held in place by bearing cages 68. Above the upper inclined faces 60 of the wedge bar 58 are blocks 70 having lower faces arranged in parallel relation to the upper inclined faces 60 of the wedge bar, and between these faces are anti-fric- 55

tion rollers 72 held in place by bearing cages 74. The blocks 70 are provided with recesses 76 (Fig. 1) shaped and arranged to receive the lower ends of vertical screws 78 (Figs. 1 and 2) which are threaded into the bracket 50 and carry lock nuts 80. The screws 78 prevent the blocks 70 from being moved laterally of the machine and the front and rear faces of the bracket prevent the blocks from being moved forward or rearward of the machine. The screws 78 provide means serving in assembling the machine to adjust the upper roll 22 which is constantly urged upward by pairs of relatively weak springs 82 (Figs. 1 and 2) with relation to the cutting edge 36 of the knife 26. The upper roll is mounted in bearings 84 which are constantly urged upwardly by the springs 82, the lower ends of which fit in bores formed in the respective arms 44. It will be appreciated that, if desirable, the lower ends of the springs 82 may be housed in the main frame 28.

The bearings 84 in which the upper roll 22 is mounted extend upwardly and are provided with inclined faces 86 extending downward and to the right, as viewed in Fig. 1. At the left side of the machine the bearing 84 is provided with an upwardly extending portion 88 (Fig. 1) in which is rotatably mounted a screw 90 (Figs. 1 and 2). The screw 90 is prevented from moving lengthwise in the bearing 84 and has a hand wheel 92 secured to its left end, as viewed in Fig. 1. The screw 90 is threaded into a nut 94 fitting in a recess 96 formed in the upwardly extending portion 88 of the left-hand bearing 84. The left-hand portion of the adjusting slide 56 is forked, as best illustrated in Fig. 3, the arms 98 of the fork passing behind and in front of the upwardly extending portion 88 of the left-hand bearing of the upper roll 22. Formed in the inner faces 40 of the adjusting slide 56 are vertical grooves 100 (Figs. 1 and 3) shaped to receive front and rear projections 102 of the nut 94. When the screw 90 is rotated the nut is moved laterally of the machine causing the slide 56 to be raised or lowered with relation to the bearings 84 of the upper roll 22 thereby initially adjusting the upper roll which, as above stated, is constantly urged upward by the springs 82, to vary the width of the gap 34.

When the work piece supported by the table 20 enters between the feed rolls 22, 24 the lower roll is moved downward about the axis of the shaft 46 (Fig. 2), the springs 48 causing the work piece to be compressed and to exert upward pressure against the upper roll 22 which is held against upward movement by the slide 56 and may be described as being non-yieldable.

In order to vary the width of the gap 34 in accordance with the density of the work piece being split there is provided mechanism which will now be described, for operatively connecting the supporting arms 44 to the wedge bar 58, the arrangement being such that movement of the lower roll 24 in one direction will cause a proportionately less movement of the upper roll in an opposite direction. In splitting heel-breast covering flaps from soles the ratio of movement of the upper roll 22 to the movement of the lower roll 24 is about one to seven, which is approximately the ratio of the thickness of the flap to the full thickness of the sole.

Each of the supporting arms 44 has extending from it a lug 104 (Fig. 2) in which is formed a recess 106 for receiving the lower end of an upwardly extending thrust rod 108. The bottom of

each recess 106 is approximately in the same horizontal plane as the axis of rotation of the lower roll 24, and the vertical axis of each recess, when viewed from the front of the machine, is arranged in a vertical plane 110 passing through the corresponding globular bearing 42 (Fig. 1). With such an arrangement upward and downward movement of one end only of the lower roll 24 does not materially affect the heightwise position of the bearing 42 at the other end of the lower roll.

The upper end of the thrust rod 108 at the right-hand side of the machine has threaded into it the lower end of a rod 112 which is secured in its adjusted position to the thrust rod by a lock nut 114. The upper end of the rod 112 is pivoted to a horizontal arm of a bell-crank lever 116 which is pivoted upon a stud 118 secured to the bracket 50. The vertical arm of the bell-crank lever 116 is pivoted to the right-hand end of a substantially horizontal link 120 pivoted to the lower end of a wedge bar lever 122 which is in the vertical position shown in Fig. 1 when the machine is idle. The wedge bar lever 122 is pivoted midway between its ends on a stud 124 (Figs. 1 and 2) secured to the wedge bar 58 which, as above described, controls the heightwise position of the upper roll 22.

The thrust bar 108 at the left side of the machine as viewed in Fig. 1 has at its upper end an enlarged portion into which is threaded a rod 126 secured in its adjusted position to the thrust rod by a lock nut 128. The rod 126 is pivoted to a horizontal arm of a bell-crank lever 130 pivoted upon a stud 132 secured to the bracket 50. A vertical arm of the bell-crank lever 130 is pivoted to the left-hand end of a substantially horizontal link 134 which is pivotally connected to the upper end of the wedge bar lever 122. The bell-crank levers 116 and 130 are identical and are arranged in parallel relation. The lower roll 24 moves upwardly when a readily compressible portion of the work piece enters between the rolls 22 and 24, the rods 108 then being moved upwardly causing the bell-crank levers 116, 130 to swing in clockwise direction. The bell-crank lever 116 thrusts the link 120 connected to it and the lower end of the wedge bar 122 toward the left, while the bell-crank lever 130 pulls through the link 134 connected to it and to the upper end of the wedge bar lever 122 toward the left and therefore moves the wedge bar 58 toward the left a distance equal to the upward movement of the lower roll. Movement of the wedge bar 58 toward the left causes the upper roll 22 to be moved downward a distance proportional to the amount of upward movement of the lower roll, the ratio of the movement of the two rolls 22, 24 in opposite directions depending upon the angle of the faces 60 and 62 (Figs. 1 and 3) of the wedge bar 58.

In the illustrated embodiment if during the splitting operation both ends of the lower roll 24 move upward and one end, in addition, moves upward relatively to the other end of the roll, owing to variations in the density of the work piece toward one side or the other, the wedge bar lever 122 will, beside being moved to the left, be swung about its pivotal connection to the link 120 or 134 connected to the other end of the lower roll, and since the two links are pivoted to the wedge bar lever at equal distances from its pivot to the wedge bar 58 the latter will, as a result of the swinging movement of the wedge bar lever 122, be moved to the left a distance equal to half

that of the additional upward movement of the end of the lower roll 24, thus bringing about a proportionate downward adjustment of the lower roll 22 corresponding to the bodily upward movement of the lower roll, plus half that of the end of the lower roll which moves upward the greater distance.

It will be clear from the foregoing that when the uniformly thick sole is of the same density widthwise, but of varying density lengthwise, the lower yieldable roll will have imparted to it translatory or bodily movement as the sole is progressively fed against the knife. When the sole is of varying density widthwise as well as lengthwise, however, the sole 24, in addition to being moved toward or away from the knife as above described, tilts widthwise of the sole during the splitting operation. The wedge bar 58, which serves as an abutment for determining the position of the gage roll 22, is thus moved into different operative positions through the yieldable feed roll and the above-described mechanism in accordance with lengthwise and widthwise variations in density of the sole.

The machine, therefore, compensates readily for variations in density extending uniformly from one side to the other of the material, and also for variations in the density of the material along one side margin or the other relatively to the opposite sides of a work piece.

In order to prevent the upper roll from being raised an undue distance from the knife when a thicker work piece than the machine is arranged to operate upon is presented to the rolls 22, 24, the wedge bar 58 has secured to it a screw 136 which projects through an opening in the left cover plate 52, as viewed in Fig. 2, and carries a nut 138 arranged to engage the cover plate and limit movement of the wedge bar toward the right.

The work piece mounted upon the table 20 is guided into the rolls 20, 24 by a pair of centralizing fingers 140 the lower ends of which are positioned just above the table. The respective fingers 140 are pivoted at 142 and are provided with intermeshing gear segments 144, the arrangement being such that the lower ends of the fingers move equal distances in opposite directions about their pivots. The lower ends of the fingers 140 are constantly urged toward each other by a spring 146, inward movement of the fingers being limited by a screw 148 which is threaded into one of the fingers.

The movement of the various parts of the above-described mechanism when a work piece enters between the rolls 22, 24 is rapid, the raising of the upper roll 22 taking place before the leading edge of the work piece has reached the cutting edge 36 of the knife 26.

The hand wheel 92 for moving the adjusting slide 58 laterally of the machine is provided with spaced notches 150 which are engaged by a leaf spring 152 secured to the upwardly extending portion 68 of the left-hand bearing of the upper roll 22. The notches 150 are so positioned that rotation of the hand wheel from one notch to the next causes the upper roll to move upward or downward $\frac{1}{4}$ of an iron, one iron being approximately $\frac{1}{48}$ of an inch. With the above arrangement the operator may quickly adjust the upper roll a desired amount if it is found by measurement of the work piece which has been split that adjustment of the roll is necessary.

In splitting heel-breast covering flaps 154 (Fig. 4) the split sole is withdrawn from the machine

in a direction opposite to the direction in which it is fed during the splitting stroke. To equip the machine for splitting flaps a pair of rolls 156, 158 and operating mechanism therefor (not shown) such as disclosed in United States Letters Patent No. 1,638,929, granted August 16, 1927, on an application filed in the names of Joseph Gouldbourn and Wilfrid Minett, are provided. The upper roll 156 has a flattened surface 160, the lower roll 158 being cylindrical throughout its periphery. The rolls are provided at their opposite ends with cams 162, 164 so arranged that when the cams are in engagement the face 166 is in opposed relation to the lower roll 158 which is depressed against the action of the springs 43. The operating mechanism for the machine is so constructed and arranged that the machine comes to a rest when the rolls 156, 158 are arranged in the positions indicated in Fig. 4, thus permitting the split sole to be removed from the machine without danger of splitting the flap 154. Since the construction and operation of the above machine is described in detail in said United States Letters Patent No. 1,638,929 it will not be necessary further to describe the same herein.

Having described the invention, what we claim as new and desire to secure by Letters Patent of the United States is:

1. In a splitting machine, a fixed knife having an elongated cutting edge, a gage member, means for initially adjusting said gage member with relation to the cutting edge of the knife to form a gap of a predetermined width in accordance with the desired thickness of a piece of material to be split from a work piece, a yieldable member mounted for bodily movement and also for tilting movement with relation to the knife in accordance with the density of or variations in the density of the material fed by said members against the knife, and means constructed and arranged to move the gage member a predetermined distance in one direction in accordance with the amount of bodily movement of the yieldable member in an opposite direction and also to move the gage member an additional distance in said one direction in accordance with the degree of tilting movement of the yieldable member in said opposite direction.

2. In a splitting machine, a knife having a cutting edge, a movable abutment, a gage roll, resilient means for moving the gage roll to a predetermined operative position in accordance with the position of the abutment, a yieldable feed roll which is constructed and arranged for bodily and also for tilting movement away from the knife under pressure of a work piece forced against the knife by said rolls, and mechanism operatively connecting the yieldable roll and the abutment, said mechanism being constructed and arranged to coordinate movement of the abutment and bodily movement of the yieldable feed roll in a predetermined ratio and also to coordinate movement of the abutment and the tilting movement of the yieldable feed roll in another predetermined ratio.

3. In a splitting machine, a fixed knife having a cutting edge, a gage roll, means for initially adjusting the gage roll with relation to the cutting edge of the knife to form a gap of a predetermined width in accordance with the desired thickness of a piece of material to be split from a work piece, a feed roll mounted for bodily movement with relation to the knife about an axis in accordance with the density of the work piece

forced by said rolls against the knife, said axis being spaced a considerable distance from the feed roll and being arranged in parallel relation to the cutting edge of the knife, and mechanism for causing movement of the feed roll in one direction to effect a proportionately less movement of the gage roll in an opposite direction.

4. In a splitting machine, a knife having a cutting edge, an abutment, a gage roll, resilient means for moving the gage roll to a predetermined position with relation to the knife in accordance with the position of the abutment, a yieldable feed roll, globular bearings for supporting the opposite ends of the yieldable feed roll, supports for said bearings, springs for constantly urging the respective supports toward the knife, and connections between the respective supports and the abutment constructed and arranged to coordinate the movement of the rolls in a predetermined ratio in opposite directions in accordance with equal movement of the supports toward or away from the knife and in another predetermined ratio in opposite directions in accordance with the differential movement of the supports toward or away from the knife.

5. In a splitting machine, a knife having an elongated cutting edge, a non-yieldable roll, means for initially adjusting said roll with relation to the cutting edge of the knife to form a gap of a predetermined width, a yieldable roll constructed and arranged to cooperate with said non-yieldable roll for feeding a work piece against the cutting edge of the knife to split said work piece, a wedge bar for limiting movement of the non-yieldable roll away from the knife, and means comprising said wedge bar constructed and arranged to cause translatory movement of the yieldable roll in one direction to effect a proportionately less movement of the non-yieldable roll in an opposite direction and also constructed and arranged to cause tilting movement of the yieldable roll to effect an additional movement of the non-yieldable roll in said opposite direction.

6. In a splitting machine, a fixed knife having a cutting edge, a roll which is initially adjustable with relation to the cutting edge of the knife to form a gap of a predetermined width between the roll and said cutting edge, a second roll arranged to cooperate with the first-named roll for forcing a work piece against the knife to split

said work piece, means for rotating said rolls, bearings in which said second-named roll is rotatably mounted, each of said bearings being individually mounted for pivotal movement about an axis, a spring for normally urging each of the bearings toward the knife, and mechanism for causing movement of the second-named feed roll in one direction to effect a proportionately less movement of the other feed roll in an opposite direction.

7. In a splitting machine, a knife having a straight cutting edge, a roll, means comprising bearings in which said roll is rotatably mounted, an abutment, springs for forcing said means against the abutment to locate said roll in a predetermined position with relation to the cutting edge of the knife, a second roll constructed and arranged to cooperate with the first-named roll for feeding a work piece against the cutting edge of the knife to split said work piece, globular bearings in which said second-named roll is rotatably mounted, said globular bearings being mounted for individual pivotal movement about an axis which is approximately parallel to the cutting edge of the knife, and mechanism which is operatively connected to the globular bearings and is constructed and arranged to move said abutment to a predetermined position in accordance with the position of the second-named roll.

8. In a splitting machine, a knife having a cutting edge, yieldable and non-yieldable rolls, bearings for supporting the opposite ends of the yieldable roll, means comprising said bearings constructed and arranged to permit the yieldable roll to move toward and away from the knife and to tilt with relation to the knife under pressure of a work piece fed by said rolls against the cutting edge of the knife, a wedge bar for determining the location of the non-yieldable roll, and means operatively connecting the bearings of the yieldable roll to the wedge bar, said means being constructed and arranged to move the wedge bar a predetermined distance in accordance with the movement in unison of the bearings and also to move the wedge bar an additional predetermined distance in accordance with the differential movement of said bearings.
